(57) CLAIM

The ornamental design for a tethered pocket for apparel, as shown and described.

DESCRIPTION

FIG. 1 is a front view in perspective of a tethered pocket for apparel showing my new design;

FIG. 2 is a rear view in perspective thereof;

FIG. 3 is a front view thereof;

FIG. 4 is a rear view thereof;

FIG. 5 is a top view thereof;

FIG. 6 is a bottom view thereof;

FIG. 7 is a first side view thereof;

FIG. 8 is a second side view thereof; and,

FIG. 9 is a front view of a jacket including the tethered pocket for apparel of FIG. 1.

The broken dashed lines in the drawings represent stitching that does not form part of the claimed design. The broken dot dash lines illustrating the jacket represent environmental structure forming no part of the claimed design. The broken dot dash lines illustrating the boundary of the tether portion of the article represent boundaries of the claimed design.

1 Claim, 6 Drawing Sheets
